UNITED STATES PATENT OFFICE.

EDWARD MARCH, OF LONDON, ENGLAND.

CHECK-DISK-ISSUING MACHINE.

1,079,943.

Specification of Letters Patent.

Patented Dec. 2, 1913.

Application filed July 15, 1913. Serial No. 779,087.

To all whom it may concern:

Be it known that I, EDWARD MARCH, subject of the King of Great Britain, residing at Nos. 17-21 Tavistock street, Covent Garden, London, England, have invented new and useful Improvements in Check-Disk-Issuing Machines, of which the following is a specification.

This invention relates to machines for issuing check-disks of the kind in which the check-disk, in being issued, operates, by engagement with the teeth of a wheel, a registering or counting device. In such a machine a ratchet-wheel is provided on the spindle of the register-wheel, which by the engagement of a pawl therewith prevents the back-rotation of the register-wheel and thereby also prevents the reinsertion of a check-disk into the slot from which it is issued. There has also been provided a pawl, which is released by a ramp on a sliding plate to protrude into the path of one of the teeth of the register-wheel, immediately prior to the complete issue of a check disk and so lock the wheel against over-running and thus preclude the wrong tooth being engaged by the next to be issued check-disk, which would result in the machine becoming jammed. As, however, three teeth of the wheel are in engagement with the check-disks during the issue of each check-disk, the pawl which prevents over-running is kept out of the path of the last of the teeth until the other two teeth have passed. This allows a very short period for the pawl to get into the operative position and consequently necessitates very accurate fitting and timing of the pawl and the ramp which displaces same.

According to the present invention, the pawl which prevents over-running is arranged to protrude into the path of the tooth with which it is to engage, immediately after the first of the three teeth has moved away, thus there is a considerably longer period for the pawl to get into position, thereby removing practically all liability of the pawl failing to arrest the register-wheel.

A machine for issuing check-disks, having the above described improvement is illustrated on the accompanying drawing, in which:

Figure 1 is a longitudinal section, Fig. 2 a front elevation and Fig. 3 an inverted plan.

a is the register-wheel, *b* are the check-disks and *c* is the slide, which on being reciprocated by a handle *d*, crank *e* and connecting rod *f*, thrusts the lowermost of the pile of check-disks *b* beneath the register-wheel *a*, whereby the check-disk *b* so advanced, pushes out the check-disk *b* previously at rest beneath the register-wheel *a*, and issues same through the issuing slot *g* of the machine, see Fig. 2. On the issue of a check-disk, the register-wheel *a* is angularly displaced, a thick tooth *a*¹ being in engagement with a central aperture of the check-disk *b* which is issued, a thin tooth *a*² being, on advancement of the check-disks, engaged by the leading edge of the next check-disk *b*, which finally comes to rest beneath the wheel, owing to the completion of the working stroke of the slide *c*, with a thick tooth in engagement with the central aperture of such check-disk. The drawing shows the register-wheel *a* in the position of rest and the slide *c* in the retracted position, from which it is about to be advanced to issue a check disk.

*h*¹ is the pawl which by engagement with the ratchet-wheel *h* on the spindle of the register-wheel *a*, precludes back-running.

Beneath the register-wheel *a* is a pawl *i*. This pawl *i* is raised by a spring *i*¹ into the path of the thick teeth *a*¹ of the register-wheel *a*, to prevent over-running thereof. The pawl *i* is in the plane of the thick teeth *a*¹, but cannot be engaged by the thin teeth *a*² of the wheel *a*, as these teeth are arranged laterally out of the plane of the pawl *i*, as shown in Fig. 2. As the pawl *i* cannot be struck by the thin teeth *a*² of the wheel *a*, as soon as one thick tooth *a*¹ has been moved away from the range of the pawl *i*, the latter can at once be set in the path of the next thick tooth *a*¹, without waiting for the intermediate thin tooth to pass. This is effected as follows:— On the retraction of the slide *c*, it strikes a shoulder *j*¹ of a sliding plate *j* and retracts the latter. A ramp *k* on the plate *j* is thereby drawn against a roller *i*² on the pawl *i*, and withdraws the latter from the path of the thick teeth *a*¹. This position of the parts is illustrated on the drawing. On the forward or working stroke of the slide *c*, a spring-raised dog *l* strikes a shoulder *m* on the slide *j* and displaces the latter and with it its ramp *k* from engagement with the roller *i*² of the pawl *i* and the pawl

i is lifted, by its spring i^1 into the path of the next thick tooth a^1 . The previously held thick tooth a^1 , will have just been slightly advanced by the advance of the two check-disk b , by the slide c . On the continued forward stroke of the slide c , the dog l is moved from engagement with the shoulder m of the sliding plate j , by a roller l^1 on the dog l riding along a fixed ramp n .

10 I claim:

1. In a check-disk issuing machine, a register-wheel, teeth on said register-wheel a plurality of which teeth are engaged by the said check-disks on issue of a check-disk, a pawl and means for permitting said pawl to protrude into the path of the last of said plurality of teeth immediately after the first of said plurality has moved away.

2. In a check-disk issuing machine, a pawl, a register-wheel, teeth on said register-wheel in the plane of said pawl, teeth on said register-wheel laterally out of the plane of said pawl and means for permitting said pawl to protrude into the path of said teeth in its plane immediately after one of said teeth in its plane has been moved away therefrom.

3. In a check-disk issuing machine, a pawl, a register-wheel, teeth on said register-wheel

in the plane of said pawl, teeth on said register-wheel laterally out of the plane of said pawl, a reciprocating slide, a sliding plate, a shoulder on said plate in the rearward path of said slide, a ramp on said plate, a dog on said slide, a shoulder on said plate in the forward path of said dog and a fixed ramp on said machine alongside the path of said dog.

4. In a check-disk issuing machine, a pawl, a register-wheel, teeth on said register-wheel in the plane of said pawl, teeth on said register-wheel laterally out of the plane of said pawl, a reciprocating slide, a sliding plate, a shoulder on said plate in the rearward path of said slide, a ramp on said plate, a roller on said pawl in the path of said ramp, a dog on said slide, a shoulder on said plate in the forward path of said dog, a roller on said dog, and a fixed ramp on said machine in the path of said roller on said dog.

In testimony whereof I have signed my name to this specification in the presence of two subscribing witnesses.

EDWARD MARCH.
